UNITED STATES PATENT OFFICE

104,970

DESIGN FOR A DRESS

Albert E. Levy, New York, N. Y.

Application April 21, 1937, Serial No. 68,905

Term of patent 3½ years

To all whom it may concern:

Be it known that I, Albert E. Levy, a citizen of the United States of America, residing in city of New York, county of New York, and State of New York, have invented a new, original, and ornamental Design for a Dress, of which the following is a specification, reference being had to the accompanying drawing, forming part thereof,

Fig. 1 is a front view of a dress showing my new design.

Fig. 2 is a rear view thereof.

The characteristic feature of my design resides in the combination on the tucked dress as shown of the specific embroidery along the front and around the sleeves as shown.

I claim:

The ornamental design for a dress substantially as shown and described.

ALBERT E. LEVY.
